US00D714944S

(12) **United States Design Patent**
Gerber et al.

(10) **Patent No.:** **US D714,944 S**
(45) **Date of Patent:** **** Oct. 7, 2014**

(54) **PORTABLE DIALYSIS CABINET**

(71) Applicant: **Medtronic, Inc.**, Minneapolis, MN (US)

(72) Inventors: **Martin T. Gerber**, Maple Grove, MN (US); **David B. Lura**, Maple Grove, MN (US); **Bryant J. Pudil**, Plymouth, MN (US); **Thomas E. Meyer**, Stillwater, MN (US); **Brian Mullins**, Minneapolis, MN (US)

(73) Assignee: **Medtronic, Inc.**, Minneapolis, MN (US)

(**) Term: **14 Years**

(21) Appl. No.: **29/446,276**

(22) Filed: **Feb. 21, 2013**

(57) **CLAIM**

We claim the ornamental design for a portable dialysis cabinet, as shown and described.

DESCRIPTION

FIG. 1 is a perspective view of a portable dialysis cabinet according to one embodiment;

FIG. 2 is a front view of the portable dialysis cabinet referenced in FIG. 1;

FIG. 3 is a rear view of the portable dialysis cabinet referenced in FIG. 1;

FIG. 4 is a left side view of the portable dialysis cabinet referenced in FIG. 1;

FIG. 5 is a right side view of the portable dialysis cabinet referenced in FIG. 1;

FIG. 6 is a top view of the portable dialysis cabinet referenced in FIG. 1;

FIG. 7 is a bottom view of the portable dialysis cabinet referenced in FIG. 1;

FIG. 8 is a perspective view of a portable dialysis cabinet according to another embodiment;

FIG. 9 is a front view of the portable dialysis cabinet referenced in FIG. 8;

FIG. 10 is a rear view of the portable dialysis cabinet referenced in FIG. 8;

FIG. 11 is a left side view of the portable dialysis cabinet referenced in FIG. 8;

FIG. 12 is a right side view of the portable dialysis cabinet referenced in FIG. 8;

FIG. 13 is a top view of the portable dialysis cabinet referenced in FIG. 8; and,

FIG. 14 is a bottom view of the portable dialysis cabinet referenced in FIG. 8.

In the drawings, the broken lines depict environmental subject matter only and form no part of the claimed design.
